UNITED STATES PATENT OFFICE

FRANZ WINNY, OF STUTTGART-BOTNANG, GERMANY, ASSIGNOR TO THE FIRM: JULIUS
GEIGER G. M. B. H., OF STUTTGART, GERMANY

GAUGE

Application filed January 6, 1930, Serial No. 418,902, and in Germany November 27, 1928.

In book printing when blocks are used which are of a lesser height than that required for the general type matter employed, said blocks must be packed up to this proper height. Hitherto it has been usual to ascertain the packings needed by trial with the block in the set up matter, a process which is awkward, and often entails rectifications after proofs have been taken.

10 The present invention obviates this trial and awkward method of packing which is not highly accurate, is a waste of time and diminishes the output capacity of the printing press, by creating a simple and ingenious device which renders it possible to ascertain the required amount of packing in the shortest possible time.

15 The accompanying drawings show as an example one constructional form of the invention.

20 Fig. 1 is a front view of the device.

Fig. 2 is a similar view with the front cover removed and

25 Fig. 3 is a plan view.

20 The essential component part of the invention is a gauge indicated generally in the drawings at 1 and includes a two armed lever 8, which is connected to an indicating device 2, 3. The gauge lever 8 is pivoted between the recessed back wall 4 and the removable front wall 5 of the housing of the instrument, on a trunnion 6 projecting from the back wall 4, and is so acted upon by a spring 7 engaging on the one hand the back

35 wall 4 and on the other hand the head at the inner end of the gauge 1, that its other extremity, which is designed as a handle, protrudes from the housing and normally abuts at the top against a stop shoulder 16 of the 40 rear wall of the housing 4. Formed on or attached to the lower part of the rear wall of the housing is a clamping jaw 9, which is provided with a clamping screw 10. By means of this clamping jaw 45 and screw it is quite easy to fix the appliance upon any plate, preferably the customary locking or closing plate 11 (that is to say where it will be in close proximity and handy to the printing press). A projecting 50 trunnion 13 on a toothed segment 22 en-

gages in a slot 12 in the gauge lever 8, and the toothed segment which is pivoted at 14 in the housing meshes with a gear wheel 15 attached to an indicating disc 2 having a scale of figures 17 on its circumference. This 55 scale is visible from the top through an aperture 18 in the top wall of the housing, a reference mark 3 being provided on the latter. A spring 20 connected on the one hand to the disc 2 and on the other hand to the pivot or trunnion 21 of the disc acts to absorb any backlash between the disc driving wheel 15 and the toothed segment 22 and also between the trunnion 13 on the toothed segment 22 and the upper edge of the slot 12 in the gauge lever, or in other words always brings about a correct reading of the disc 60 independently of any play in its actuating members.

65 The gauge lever 8 is pivoted on an eccentric boss 23 having the trunnion 6, the latter outside of the front wall of the housing being fitted with an adjusting segment 24 having an arcuate slot 25, in which works a fixing screw 19, the segment being provided with a handle 26. On the curved bottom face 27 of the gauge a celluloid strip 28 is 70 removably fixed.

75 In operation the gauge at the handle end of the lever 8 is first pressed down and a standard block 29 corresponding to the required height of the type matter is inserted between the celluloid facing strip 28 and the plate 11. The gauge lever when released adjusts itself by reason of the action of the spring 7 to the standard and gives a certain reading on the indicator disc 2, the movement of the lever 8 of the gauge around its pivot 6 being transmitted by the toothed segment 22 and the gear 15. After loosening the fixing screw 19 the eccentric boss 23 is turned the amount necessary to bring the zero line of the indicator disc into register with the reference mark 3 on the housing, whereupon the screw 19 is tightened. Now the standard block 29 is removed and the printing block, the amount of packing for which is to be ascertained is, with its printing face uppermost inserted in its place. The gauge lever 85 again moves into contact with the block and 90

- shows an indication on the scale 2 which differs from the formerly adjusted zero position. Now a number of flat packing plates are inserted between the printing block and 5 the gauge until the zero reading on the indicator disc is again reached. Then the height of the printing block together with the packing plates corresponds accurately to the required height, that is to say it is only necessary to insert the printing block with the said packing plates into the form, and it will accordingly correspond in height with the other parts of the type matter, and thus produce a perfect print.
- 10 15 The construction of the gauge in the form of a double armed lever and the use of the eccentric adjusting arrangement permits a very simple design of the whole apparatus and makes its manipulation easy.
- 20 25 By the use of a rotating disc as the essential part of the indicating device, it is possible to extend the scale around the whole circumference, thus saving space and giving better legibility. The purpose of rounding off the gauge face is to enable the gauge always to lie tangentially to the standard block or the printing block and its packings, in such a manner that the measurement is sure always to be accurate. The celluloid facing 30 35 on the gauge lever protects the printing face of the block from damage. The vertical face 30 of the appliance to which the printing block can be fitted sideways, makes it possible to ascertain whether the sides of the printing block are accurately at right angles to its base, for the purpose of preventing the squeezing out when the block whose sides 40 45 are not accurately square is inserted in its space in the matter, by reason of the lateral thrust then occurring. It is also possible by means of an auxiliary scale 32 starting from the zero point to use the apparatus for measuring the exact thickness of the so-called printing cylinder covering, that is the soft 50 55 coverings fixed to the printing cylinders for the purpose of protecting the type, such covering being of a thickness of the order of 1 to 2 mm.
- When taking such measurements it is only 55 60 necessary, after having put the device into the zero position in conjunction with a standard block to insert the said coverings between the standard block 29 and the gauge, it being then easy to read off the thickness of the covering.
- I claim:
1. An instrument of the kind described, comprising a housing; a tensioned gauge lever in the housing and having a rounded outer end protruding from the housing and adapted to contact with the work; a trunnion mounted in the housing and having an adjustable eccentric pivotally supporting the lever; an indicator mechanism operatively connected with the lever; and a setting device 65 70 75 80 85 90 95 100 105 110 115 120 125 130

2. An instrument of the kind described, comprising a housing; a tensioned gauge lever in the housing and having a rounded outer end protruding from the housing and adapted to contact with the work; a trunnion mounted in the housing and having an adjustable eccentric pivotally supporting the lever; an indicator mechanism operatively connected with the lever; and a setting device exteriorly of the housing for the eccentric. 70 75 80 85 90 95 100 105 110 115 120 125 130
3. An instrument of the kind described, comprising a housing; a tensioned gauge lever in the housing and having a rounded outer end protruding from the housing and adapted to contact with the work; a trunnion mounted in the housing and having an adjustable eccentric pivotally supporting the lever; an indicator mechanism operatively connected with the lever; a setting device exteriorly of the housing for the eccentric; and means on the housing for clamping it in working relation to a piece of work. 80 85 90 95 100 105 110 115 120 125 130
4. An instrument of the kind described, comprising a housing; a tensioned gauge lever in the housing and having a rounded outer end protruding from the housing and adapted to contact with the work; a trunnion mounted in the housing and having an adjustable eccentric pivotally supporting the lever; an indicator mechanism operatively connected with the lever; a setting device exteriorly of the housing for the eccentric; means on the housing for clamping it in working relation to a piece of work; and means for preventing lost motion between the indicator mechanism and the lever. 90 95 100 105 110 115 120 125 130
5. An instrument of the kind described, comprising a housing; a tensioned gauge lever in the housing and having a rounded outer end protruding from the housing and adapted to contact with the work; a trunnion mounted in the housing and having an adjustable eccentric pivotally supporting the lever; an indicator mechanism operatively connected with the lever; a setting device exteriorly of the housing for the eccentric; means on the housing for clamping it in working relation to a piece of work; and means for preventing lost motion between the indicator mechanism and the lever; said housing having a work receiving space opening through its base and having a perpendicular edge confronting the rounded end of the lever. 100 105 110 115 120 125 130
6. An instrument of the kind described, comprising a housing; a tensioned gauge lever in the housing and having a rounded outer end protruding from the housing and adapted to contact with the work; a trunnion mounted in the housing and having an adjustable eccentric pivotally supporting the lever; an indicator mechanism operatively connected with the lever; a setting device exteriorly of the housing for the eccentric; means on the housing for clamping it in

working relation to a piece of work; means for preventing lost motion between the indicator mechanism and the lever, said housing having a work receiving space opening through its base and having a perpendicular edge confronting the rounded end of the lever; and a removable protective strip covering the rounded end of said lever.

5 7. An instrument of the kind described, comprising a housing having a sight opening in its top; a tensioned gauge lever in the housing and having a rounded outer end protruding from the housing and adapted to contact with the work; a trunnion 10 mounted in the housing and having an adjustable eccentric pivotally supporting the lever; an indicator mechanism operatively connected with the lever and readable through the sight opening; and a setting device exteriorly of the housing for the eccentric.

15 In testimony whereof I affix my signature.
FRANZ WINNY.
